UNITED STATES PATENT OFFICE.

MICHEL LARONDE, OF ANICHE, FRANCE, ASSIGNOR TO SOCIETE ANONYME DES VERRERIES ET MANUFACTURES DE GLACES D'ANICHE, OF ANICHE, FRANCE.

MACHINE FOR LADLING AND POURING PURPOSES.

Application filed July 11, 1927, Serial No. 204,944, and in France April 22, 1927.

The present invention relates to a machine which is adapted for taking up or ladling a substance in a recipient and for transporting the same and then pouring it out at the place of use. The said machine, which may be termed a combined ladling and pouring apparatus, is so disposed that it may be utilized in all manufacturing plants, irrespectively of the relative positions of the recipient and of the place at which the material is to be poured.

The said apparatus comprises a main frame adapted to travel upon rails, upon which is mounted a suitable carriage which is transversally movable with reference to the rails; upon the said carriage is disposed a pivoted platform upon which are mounted the several mechanical parts by which the ladling and pouring operations are effected.

The ladle which serves to take up the material and to pour it out at the place of utilization is mounted on the end of an arm which is connected with a rotatable shaft disposed in a sleeve; the latter is pivotally mounted on what is termed the pouring axis which is placed parallel with the shaft of the sleeve and is pivoted to an element designated as the cradle which is pivotally mounted on a support secured to the said platform. Due to the inclination thus given to the arm of the ladle, combined with the rotation of the said arm, the ladling operation can be suitably performed.

Compressed air is preferably employed for controlling the various movements of the ladle, so that without requiring the use of reducing gear or like devices, the ladle can be given a very easy motion which obviates all formation of air bubbles in the material when in the pasty state.

The appended diagrammatic drawings show by way of example an embodiment of the invention consisting of a machine for the ladling of glass in a melting furnace and for pouring it upon the table of a plate glass machine.

Fig. 1 is a side elevational view of the machine, and

Fig. 2 is a partial plan view.

Fig. 3 is a partial side view of the machine on the opposite side from the one shown in Fig. 1, and

Fig. 4 is a corresponding partial plan view.

Fig. 5 is a vertical section on the line 5—5 of Fig. 3.

Figs. 6 to 10 are diagrammatic views relative to the different movements of the ladle.

The said machine comprises a main frame 1 which is adapted to travel upon the rails 2 in front of the furnace whose outer wall is shown at 3. Upon the said main frame is movable transversally to the rails 2 a carriage 4 upon which is pivotally mounted the circular platform 5. The control of the motion of the main frame and of the carriage, as well as the pivotation of the platform is effected by electric means from a control post or cabin which is mounted on an extension 6 of said platform and contains all the necessary controlling devices and the like, which are operated by a single person, and the latter is further provided in the cabin with the cocks for the admission and discharge of compressed air which serves—by means which will be further described—to impart all the necessary movements to the ladle; the operator can also control from the cabin the opening and closing movements of the furnace for the proper handling of the ladle.

To the said platform, and on the side opposite the cabin, is bolted the supporting bracket 7 which is provided at its base with four screw jacks with square threads by which the machine may be adjusted according to the respective heights of the melted glass in the furnace and the upper edge of the pouring table of the plate glass machine.

The bracket 7 is provided with two bearings coaxing with the trunnions 9 of a device 10 or cradle which is given a special shape in accordance with the proper mechanical strength and also to provide for its pivotation, and that of the parts which it carries, upon the trunnions 9.

The said cradle supports a sleeve provided with two bearings whose centre line can be made eccentric with reference to the device 11 when for any reason it is necessary to adjust the height of the axis of the machine within restricted limits. In the said bearings is mounted a shaft 12 to which is secured the rod or beam 13 by a tapered socket fit and key, said beam supporting the ladle 14 of elliptical section.

At its end opposite the one to which the beam 13 is secured, the shaft 12 carries a special pinion 15 whose number of teeth is determined by the amplitude of the motion, and which carries at its periphery the two notches 15^a and 15^b coaxing with a pawl 16.

(Figs. 6-10) which is mounted on the said sleeve, the 180-degree spacing of the said notches determines the extreme positions of the ladle when rotating on its axis.

- 5 The sleeve 11 is connected with the cradle by two cheeks 17 keyed to a secondary shaft 18 which will be herein designated as the pouring shaft; said shaft which is parallel with the shaft 12 and hence with the sleeve 10 70
11 is mounted in bearings pertaining to the cradle 10 and its distance from the shaft 12 somewhat exceeds one-half the smaller axis of the mouth of the ladle, and in this manner the sleeve, the beam and the ladle may be actuated by suitable means so as to rotate on the axis of the pouring shaft whose extension is situated near the lip of the ladle. This offers an advantage consisting in the fact that when the ladle is being emptied, 75
20 the height of pouring of the glass will remain constant adjacent the pouring lip.

The weight of the sleeve, the shaft 12, the beam 13 and the ladle 14 is balanced by a counterweight 19 disposed between the 25 cheeks 17.

To the pouring shaft 18 is keyed a toothed quadrant 20 coacting with a rack 21 attached to the rod of a piston movable in a double-acting cylinder 22 connected with the cradle 30 and provided with the damping means whose object will be further described.

The compressed air necessary to operate the piston coacting with the said rack is supplied by a compressor 23 which is mounted 35 on the platform 5 and is driven by an electric motor, and the air is stored in two tanks 24 placed on either side of the cabin.

Upon the pouring shaft is loosely mounted the gear wheel 25 carrying an even number 40 of teeth and also four notches 25^a-25^b-25^c-25^d-on its periphery; the said wheel, whose diameter is double the diameter of the pinion 15, is in gear engagement with the said pinion.

45 In order that the rotation of the ladle on its axis shall co-operate with the pivotation of the cradle 10 on its trunnions 9, the pouring shaft has loosely mounted thereon a strap 26 between whose branches is disposed 50 the wheel 25 and which is provided with a counterweight 27 and a pawl 28 coacting with the notches 25^a, and 25^d (Figs. 6 to 10). Outwardly of the pinion 15 there is 55 disposed upon the shaft 18 a suitably balanced hand wheel 29 for the hand control of the said shaft in case the compressed air supply should fail. The strap 26, although loose on the shaft 18 is held in a well-determined position inasmuch as it is connected 60 with a fixed point of the platform 5 by a link 30 of adjustable length.

The pawl 28 which is so disposed as to transmit the power to the wheel 25, has a suitable shape enabling it to engage in 65 any one of the four notches of the wheel and

to remain therein if the resulting impulse tends to rotate the wheel 25 in the clockwise direction, and on the contrary to be disengaged therefrom when the wheel is urged in the opposite direction.

70 The pinion 15 can only be rotated when the pawl 16 is disengaged from the notches 15^a and 15^b, and the shape of the said notches and the shape and position of the pawl 16 are such that the pawl will be released when the pinion 15 rotates in the clockwise direction, and inversely, i. e. the movement is the contrary of the aforesaid movement of the wheel 25 and the pawl 28.

The pivotation of the cradle and the sleeve 80 on the trunnions 9 for ladling purposes is controlled by the bell-crank lever 31 which is pivotally mounted at 32 between two cheeks 33 secured to the platform 5 below and in the rear of the said cradle; the said lever 85 actuates the cradle by means of the link 34 which is engaged between the branches of a fork which is formed on the corresponding end of the lever 31.

The other end of the said lever is attached 90 to a sliding member which is movable horizontally by means of the piston 36 to which it is connected by the rod 37 and which is movable in a compressed air cylinder 38 which is mounted upon the rotating platform below the said cradle.

95 For reasons which will be further stated, the sleeve may be fastened to the cradle, at the beginning of the ladling operation, by a fastening device which automatically releases the sleeve from the cradle at the end of the ladling operation, so that the glass may be suitably poured. The said fastening device is controlled by the bell-crank lever 31, and it thus depends upon the motion of the piston 36; for this purpose, the lever 31 carries a trunnion 39 to which is pivoted the head of a small link 40 which draws with it a rod 41 provided with a ring 42 carrying an arm 43; said rod is disposed horizontally above the cylinder 38 and is supported by the latter and also by two bronze rings whereof one is shown at 44 in Fig. 3.

100 The fastening device itself consists of a round rod 45 carrying at its ends two stout members 46-47 which are mounted thereon and constitute a double clamp; said rod is held parallel with the lateral face of the cradle 10, in two bearings 48 mounted thereon, and it is held against sliding by the two stop rings 49; it may thus be moved by the fork 50 disposed at its lower part and rotatable thereon under the action of the arm 43 actuated by the lever 31.

105 In these conditions, the device is fastened when the clamp 46 is disposed at the lower part and below the cradle, and the clamp 47 engages upon a nib 51 screwed into the sleeve.

Since the apparatus must be fastened and released immediately at the beginning and at the end of the dipping operation, without allowing the fork of the fastening member to hinder the motion of the piston, I take measures to accelerate the impulse brought upon the said fork by means of a counterweight 52 which ceases to exercise its balancing action at a given time.

For this purpose, the cradle carries a support carrying at the middle a trunnion upon which is pivotally mounted below the middle of its length a rod 53 carrying a counterweight 52; said rod passes through two apertured members whereof one is secured to the rod 45 and the second 55 is secured as a controlling fork to the lower ring through which is inserted the rod 45. The counterweight 52, which is in the position of equilibrium according to the vertical direction, may also be held at two other extreme points depending upon the position of the members 54 and 55.

In short, the arm 43 drives in the first place the fork 50 of the said fastening member and hence the pivoted member 55—these two members being mounted on the same ring—and the counterweight 52 will be inclined to the right or left according to the case and is thus brought into the vertical position.

The apparatus being thus unbalanced, the counterweight descends and rapidly rotates the fastening member 45, and when it holds the cradle and the nib 51 of the sleeve between its two ends, the two bearings 48, after their pivotation, will hold the rod 53 of the counterweight in either of its extreme positions. During this time, the fork is so disposed that the arm 43 will be released therefrom, but its position is such that for releasing purposes the said arm may return to its position of contact from the start of the inverse stroke of the piston, this being necessary to return the ladle to the horizontal position for its removal from the furnace.

The operation of the machine is as follows:—

To facilitate the description of the functioning, and to determine the relative positions of the several parts during their movements, it will be admitted once for all in the following description that the explanation is given by the operator who is stationed in the cabin and observes the ladle in the direction of the beam 13.

With the machine in the inoperative position as shown in Fig. 6, the ladle 14 is turned about; the beam 13 and the sleeve 11 are held in the horizontal position since the cradle 10 is maintained in equilibrium on its trunnions 9 by the bell-crank lever 31. In this position, the piston 36 of the compressed air cylinder 38 is at the end of its rear stroke, on the side next the cabin (Figs. 3, 4 and 5).

If the ladle is placed in the furnace by moving the carriage 4 upon the frame 1, the ladling operation may be commenced by the use of a special cock to supply compressed air upon the rear face of the piston 36; the cradle thus rises by pivoting on the trunnions 9, and the motion continues until the lever 31 has the position shown in dot and dash lines in Fig. 3; the said lever constantly holds the device in the equilibrated position and all vibration of the ladle in the melted glass is thus obviated. During the descent, the ladle is rotated in such manner that its edge makes contact with the glass at an angle of 40 degrees.

During the motion of the piston 36 to the right of Fig. 3, the device for securing the sleeve to the cradle has operated.

The motion of the ladle, which is a resultant motion obtained by the use of a ratchet system for combining the downward motion with the rotation of the ladle, takes place as follows:—

When under the action of the piston 36 starting from the end of the rearward stroke of the cylinder 38 the lever 31 causes the pivotation of the cradle, the pouring shaft 18, the gear wheel 25 and the strap 26 are controlled with the cradle; but since the strap is held by the link 30 it will result that its pawl 28—inasmuch as it is engaged in the notch 25^a of the wheel 25—will rotate the latter by 90 degrees on the pouring shaft during the downward motion of the ladle. This rotation takes place in the counter-clockwise direction; the wheel 25 draws with it, but in the contrary direction, the pinion 15 which is keyed to the shaft of the ladle, since in this event the pawl 16 can slide out of the notch 15^a. Since the ratio between the diameters of the wheel and pinion is 1/2, when the wheel 25 turns through 90 degrees the pinion 15 turns through 180 degrees, and the ladle is now completely overturned (Fig. 7).

Otherwise stated, starting from the position shown in Fig. 6, since the pawl 28 engaged in the notch 25^a has rotated the wheel 25, the said notch which was situated on the horizontal axis now comes into the lower position upon the vertical axis. During this time, the pinion 15, which is released from its pawl 16 due to the direction of rotation, has now turned through 180 degrees and the notch 15^b now occupies the place of the notch 15^a into which the end of the pawl 16 has now dropped.

When the ladle is inclined so as to dip into the glass, it may happen that due to the greater or less viscosity of the glass the reaction on the ladle amplified by the length of the beam 13 may counterbalance the preponderating effect of the weight of the sleeve 11 on the counterweight 19, so that the pouring device will tend to become disengaged;

the driving wheel 25 no longer occupies the initial position corresponding to the engagement of the pawl 28 in the notches 25^a or 25^c according to the case, and the pinion 15 with its pawl 16 will be unable to return, after the ladling action, into the position assigned to them for obtaining the regular movements of the ladle so that it will be filled with a uniform amount of glass. This 10 defect is obviated by the method of fastening the sleeve to the cradle.

At the end of the ladling operation, the piston 36 being at the end of its forward stroke and the lever 31 having the position 15 symmetrical with the one shown in Fig. 3, the ladle is now immersed in the melted bath and will be full of glass; it must now be raised by bringing the piston 36 to the left of Fig. 3 so as to return the lever 31 to the 20 initial position.

The cradle device carrying the pouring shaft, the wheel 25 and the strap 26 is thus brought into the horizontal position.

Since this operation is the contrary of the 25 preceding, the pawl 28 has been released, in the mean time from the notch 25^a and has dropped into the next notch 25^b situated at 90 degrees and is held therein. Since the pinion 15 has not been driven in one direction or the other by the wheel 25, it will still be held by its pawl 16 situated in the notch 15^b, so that the ladle filled with glass 30 will be held in the horizontal position (Fig. 8), and it may then be removed from the 35 furnace under proper conditions by the backward motion of the carriage 4. In fact, none of the parts can move except by an outside agent. The piston 36 is at the end of its stroke and is held by the air contained in 40 the device; the two gear wheels 15 and 25 are held by their respective pawls 16 and 28 which are maintained in their notches; the machine is now ready for the pouring operation.

45 For this operation, the piston of the double-acting cylinder 22 pertaining to the cradle actuates by the rack 21 the toothed quadrant 20 keyed to the pouring shaft 18, drawing with it in its rotation the sleeve 50 of the ladle shaft which is connected therewith by the two cheeks 17. To obtain the inverse motion after the pouring, the sleeve starts from its upper position and comes 55 into its initial position in the cradle by the action of the rack 21, in combination with the action of the damping device provided on the cylinder 22 and consisting for example of a ball which throttles the compressed air outlet.

60 With the ladle in the horizontal position for its removal, air is admitted into the cylinder 22 by a cock (which is not the same as the cock used for the ladling); by the action of the rack 21 which is secured to the 65 piston, the said quadrant will cause the

sleeve and the ladle to describe an arc of a circle about the pouring shaft; this rotation takes place in the counter-clockwise direction, and the ladle will be pivoted about its edge, thus moving through 90 degrees 70 and pouring out its contents.

In this pivoting motion, the strap 26 which is not urged will remain in position, but the pinion which is actuated by the rotation on the pouring shaft will tend to act as a planetary pinion for the gear wheel 25 and to rotate in the counter-clockwise direction, whereby the pawl 16 will be held in the notch 15^b which it already occupied. By an effect of reaction, the wheel 25 is actuated by 75 the pinion 15 (which is held against rotation) so that the pawl 28 which is released from the notch 25^b will slide and will drop into the notch 25^c (Fig. 9). At the end of this movement, since the pawls 28 and 16 80 are held in position, one in the notch 25^c and the other in the notch 15^b; the ladle is now empty, and it is to be brought into the initial position (with the sleeve placed directly in the cradle and the ladle in the inverted position) and then cooled.

Under the action of the rack 21, the sleeve and the shaft return to the initial position by a movement which is contrary to the preceding. The wheel 25 is held in the fixed 95 position by its pawl 28, and due to the reaction of the planetary pinion 15 the latter turns through 180 degrees in the clockwise direction since the pawl 16 is enabled to leave the notch 15^b and to slide into the notch 100 15^a. At the end of this operation, the respective positions of the pawls are as follows: The pawl 28 is held in the notch 25^c and the pawl 16 has returned into the notch 15^a (Fig. 10).

105 This figure is similar to Fig. 6. The pawl 16 is again engaged in the notches 15^a, and the pawl 28 has moved from the notch 25^a, to the notch 25^c situated upon the same horizontal diameter, the gear wheel 25 being 110 loose upon the shaft 18; this will have no effect, and by referring to Figs. 6-10 it will be noted that the notches 25^b-25^d serve for the intermediate positions, but that at the end or the beginning of a complete operation, the pawl 28 will always be engaged in the notch 25^a or 25^c.

115 Before returning to the furnace to begin another ladling operation, the carriage carries the ladle towards the place where the 120 movements for emptying the bottom of the ladle are effected as shown in Fig. 10.

The ladle must now be cooled, and for this purpose, by the proper operation of the carriage and the platform, the ladle is placed 125 under a hood provided with pressure water piping by which the ladle can be given an abundant shower both inside and outside.

130 From what precedes it will be observed that the whole adjustment of the machine

depends upon the length of the link 30 (which is regulated once for all) and upon the distance between its point of rotation upon the strap 26 and the center of the 5 wheel 25.

During the pouring operation, the pivoted link which is thus adjusted will serve as a support or strut by which the whole mechanism will be held in the horizontal position with reference to the axis of pivotat-

10 The position in space of the trunnion connecting the head of the link 30 with the strap 26 will remain constant, and during the rotation of the said strap, only its pawl 15 28 which is urged in one or the other direction may be engaged with or released from the said notches, thus determining the degree of relative rotation of the gear wheels 25 and 15.

20 By adding to the machine a second driving wheel similar to 25 and symmetrical with the latter about the main axis, the ladling may be performed at one edge of the ladle and the pouring at the other edge, and this 25 is advantageous from the fact that if air bubbles are produced in the glass during the ladling operation and at the side adjacent the lip, such bubbles will not move forward and will remain at the bottom of the 30 ladle.

Having thus described my apparatus, what I claim as new therein, and my own invention, is:

1. In a machine adapted to remove material from a recipient and to pour it out at the place of use, the combination of a main frame traveling upon rails, a carriage mounted upon said frame and laterally movable with reference to the rails, a platform 35 pivotally mounted on the said carriage, a beam disposed on said platform, a ladle mounted at the outer end of said beam, and means imparting three different movements to the said beam, comprising a movement of 40 rotation around its longitudinal axis, a tipping movement around a cross axis, and a partial circular movement about a shaft which is parallel with the longitudinal axis 45 of said beam.

50 2. In a machine adapted to remove material from a recipient and to pour it out at the place of use, the combination of a main frame traveling upon rails, a carriage mounted upon said frame and laterally movable with reference to the rails, a platform 55 pivotally mounted on the said carriage, a beam disposed on said platform, a ladle mounted at the outer end of said beam, and means imparting three different movements 60 to the said beam, comprising a movement of rotation around its longitudinal axis, a tipping movement around a cross axis, and a partial circular movement about a shaft which is parallel with the longitudinal axis 65 of said beam, a shaft secured to the said

beam, a sleeve in which the said beam is rotatable, a pinion mounted on the end of the said shaft opposite the end which is secured to the said beam and having two notches formed in its periphery which are spaced at 70 180 degrees, and a pawl coacting with said notches.

3. In a machine adapted to remove material from a recipient and to pour it out at the place of use, the combination of a main frame traveling upon rails, a carriage mounted upon said frame and laterally movable with reference to the rails, a platform 75 pivotally mounted on the said carriage, a beam disposed on said platform, a ladle 80 mounted at the outer end of said beam, and means imparting three different movements to the said beam, comprising a movement of rotation around its longitudinal axis, a tipping movement around a cross axis, and a 85 partial circular movement about a shaft which is parallel with the longitudinal axis of said beam, a shaft secured to the said beam, a sleeve in which the said beam is rotatable, a cradle supporting the said member, two trunnions provided on said cradle for the pivotat-

90

tion of the latter together with the said sleeve, a supporting bracket in

which the said trunnions are mounted, said bracket being secured to the said carriage of

95 the machine, and jack-screws for adjusting the height of said bracket above the said frame.

4. In a machine adapted to remove material from a recipient and to pour it out 100 at the place of use, the combination of a main frame traveling upon rails, a carriage mounted upon said frame and laterally movable with reference to the rails, a platform pivotally mounted on the said carriage, a beam disposed on said platform, a ladle mounted at the outer end of said beam, and means imparting three different movements to the said beam, comprising a movement of 105 rotation around its longitudinal axis, a tipping movement around a cross axis, and a partial circular movement about a shaft which is parallel with the longitudinal axis of said beam, a shaft secured to the said beam, a sleeve in which the said beam is

110 rotatable, a cradle supporting the said member, two trunnions provided on said cradle for the pivotat-

115

ion of the latter together with the said sleeve, a pouring shaft parallel with the said sleeve, side cheeks keyed to said

120 sleeve and adapted to connect it with the said pouring shaft, two bearings provided upon said cradle and cooperating with the said pouring shaft, the distance between the

125 said pouring shaft and the said shaft of the sleeve being slightly greater than the length of the smaller axis of the elliptical mouth of the said ladle.

5. In a machine adapted to remove material from a recipient and to pour it out 130

at the place of use, the combination of a main frame traveling upon rails, a carriage mounted upon said frame and laterally movable with reference to the rails, a platform pivotally mounted on the said carriage, a beam disposed on said platform, a ladle mounted at the outer end of said beam, and means imparting three different movements to the said beam, comprising a movement of 10 rotation around its longitudinal axis, a tipping movement around a cross axis, and a partial circular movement about a shaft 75 which is parallel with the longitudinal axis of said beam, a shaft secured to the said beam, a sleeve in which the said member is rotatable, a cradle supporting the said sleeve, two trunnions provided on said cradle for the pivotatation of the latter together with the said sleeve, a pouring shaft parallel with 15 the said sleeve, side cheeks keyed to said sleeve and adapted to connect it with the said pouring shaft, two bearings provided upon said cradle and cooperating with the said pouring shaft, the distance between the 20 said pouring shaft and the said shaft of the sleeve being slightly greater than the length of the smaller axis of the elliptical mouth of the said ladle, a counterweight adapted to 25 balance the weight of the said sleeve of the said beam, and of the ladle, said counterweight being also connected with the sleeve 30 by the said cheeks.

6. In a machine adapted to remove material from a recipient and to pour it out at the place of use, the combination of a main frame traveling upon rails, a carriage mounted upon said frame and laterally movable with reference to the rails, a platform pivotally mounted on the said carriage, a beam disposed on said platform, a ladle mounted at the outer end of said beam, and means imparting three different movements to the said beam, comprising a movement of 35 rotation around its longitudinal axis, a tipping movement around a cross axis, and a partial circular movement about a shaft 100 which is parallel with the longitudinal axis of said beam, a shaft secured to the said beam, a sleeve in which the said beam is rotatable, a cradle supporting the said sleeve, two trunnions provided on said cradle for the pivotatation of the latter together with the said sleeve, a pouring shaft parallel with 40 the said sleeve, a toothed sector keyed to the said pouring shaft, a rack cooperating with the said sector, a piston directly secured to said rack, a double-acting compressed air cylinder mounted on the said cradle and coacting with said piston, and a damping device 45 disposed upon said cylinder for regulating the exhaust.

7. In a machine adapted to remove material from a recipient and to pour it out at the place of use, the combination of a main frame traveling upon rails, a carriage

mounted upon said frame and laterally movable with reference to the rails, a platform pivotally mounted on the said carriage, a beam disposed on said platform, a ladle mounted at the outer end of said beam, and means imparting three different movements to the said beam, comprising a movement of rotation around its longitudinal axis, a tipping movement around a cross axis, and a partial circular movement about a shaft 75 which is parallel with the longitudinal axis of said beam, a shaft secured to the said beam, a sleeve in which the said beam is rotatable, a pinion mounted on the end of the said shaft opposite the end which is secured 80 to the said beam and having two notches formed in its periphery which are spaced at 180 degrees, and a pawl coacting with said notches, a cradle supporting the said sleeve, two trunnions provided on said cradle for 85 the pivotatation of the latter, a pouring shaft parallel with the said sleeve, side cheeks keyed to the said sleeve and adapted to connect it with the said pouring shaft, a gear wheel which is loose on the said pouring 90 shaft, said wheel having an even number of teeth and coacting with the said pinion mounted on the shaft of the sleeve, and provided at the periphery with four notches spaced 90 degrees apart. 95

8. In a machine adapted to remove material from a recipient and to pour it out at the place of use, the combination of a main frame traveling upon rails, a carriage mounted upon said frame and laterally movable with reference to the rails, a platform pivotally mounted on the said carriage, a beam disposed on said platform, a ladle mounted at the outer end of said beam, and means imparting three different movements to the said beam, comprising a movement of rotation around its longitudinal axis, a tipping movement around a cross axis, and a partial circular movement about a shaft 100 which is parallel with the longitudinal axis of said beam, a shaft secured to the said beam, a sleeve in which the said beam is rotatable, a pinion mounted on the end of the said shaft opposite the end which is secured to the said beam and having two notches formed in its periphery which are spaced at 180 degrees, and a pawl coacting with said notches, a cradle supporting the said sleeve, two trunnions provided on said 105 cradle for the pivotatation of the latter, a pouring shaft parallel with the said sleeve, side cheeks keyed to the said sleeve and adapted to connect it with the said pouring shaft, a gear wheel which is loose on the said pouring shaft, said wheel having an even number of teeth and coacting with the said pinion mounted on the shaft of the sleeve, and provided at the periphery with four notches spaced 90 degrees apart, a strap 110 between whose branches the said gear wheel is 115 disposed. 120

125

130

mounted, said strap being mounted on the said pouring shaft, a counterweight mounted on said strap, a pawl disposed upon the said strap and coacting with the notches of the 5 said gear wheel.

9. In a machine adapted to remove material from a recipient and to pour it out at the place of use, the combination of a main frame traveling upon rails, a carriage 10 mounted upon said frame and laterally movable with reference to the rails, a platform pivotally mounted on the said carriage, a beam disposed on said platform, a ladle mounted at the outer end of said beam, and 15 means imparting three different movements to the said beam, comprising a movement of rotation around its longitudinal axis, a tipping movement around a cross axis, and a partial circular movement about a shaft 20 which is parallel with the longitudinal axis of said beam, a shaft secured to the said beam, a sleeve in which the said beam is rotatable, a pinion mounted on the end of the said shaft opposite the end which is secured to the said beam and having two 25 notches formed in its periphery which are spaced at 180 degrees, and a pawl coacting with said notches, a cradle supporting the said sleeve, two trunnions provided on 30 said cradle for the pivotation of the latter, a pouring shaft parallel with the said sleeve, side cheeks keyed to the said sleeve and adapted to connect it with the said pouring shaft, a gear wheel which is loose on the 35 said pouring shaft, said wheel having an even number of teeth and coacting with the said pinion mounted on the shaft of the sleeve, and provided at the periphery with four notches spaced 90 degrees apart, a strap 40 between whose branches the said gear wheel is mounted, a link of adjustable length which is adapted to maintain the said strap in position, the length of said link being adjusted once for all when the machine is 45 put in service, said link being pivoted at one end to the said strap and at the other end at a fixed point on the said rotatable platform.

10. In a machine adapted to remove material from a recipient and to pour it out at the place of use, the combination of a main frame traveling upon rails, a carriage mounted upon said frame and laterally movable with reference to the rails, a platform pivotally mounted on the said carriage, a beam disposed on said platform, a ladle mounted at the outer end of said beam, and 55 means imparting three different movements to the said beam, comprising a movement of

rotation around its longitudinal axis, a tipping movement around a cross axis, and a partial circular movement about a shaft 60 which is parallel with the longitudinal axis of said beam, a shaft secured to the said beam, a sleeve in which the said beam is rotatable, a cradle supporting the said sleeve, two trunnions provided on said cradle for the pivotation of the latter together with the said sleeve, a supporting bracket in which the said trunnions are mounted, said bracket being secured to the said main frame of the machine, and jack-screws for adjusting the height of said bracket above the said frame, a link pivoted to said cradle, a right-angled 65 lever pivoted at one end to said link, a slide pivoted to the other end of said lever, and a compressed air piston adapted to act upon the said slide.

11. In a machine adapted to remove material from a recipient and to pour it out at the place of use, the combination of a main frame traveling upon rails, a carriage mounted upon said frame and laterally movable with reference to the rails, a platform 80 pivotally mounted on the said carriage, a beam disposed on said platform, a ladle mounted at the outer end of said beam, and means imparting three different movements to the said beam, comprising a movement of 85 rotation around its longitudinal axis, a tipping movement around a cross axis, and a partial circular movement about a shaft 90 which is parallel with the longitudinal axis of said beam, a shaft secured to the said beam, a sleeve in which the said beam is rotatable, a cradle supporting the said sleeve, two trunnions provided on said cradle for the pivotation of the latter together with the said sleeve, a supporting bracket in which 95 the said trunnions are mounted, said bracket being secured to the said main frame of the machine, and jack-screws for adjusting the height of said bracket above the said frame, a link pivoted to said cradle, a right-angled 100 lever pivoted at one end to said link, a slide pivoted to the other end of said lever, and a compressed air piston adapted to act upon the said slide, an automatic fastening device 105 acted upon by the said piston and adapted to connect the said sleeve with the said cradle for the ladling operation, said device being adapted to automatically disconnect these two parts in order to perform the pouring operation.

In testimony whereof I have hereunto affixed my signature.

MICHEL LARONDE.
